UNITED STATES PATENT OFFICE.

HOVAGIN SAKALIAN, OF NEW YORK, N. Y.

LOCK.

Application filed July 1, 1922. Serial No. 572,227.

To all whom it may concern:

Be it known that I, HOVAGIN SAKALIAN, a citizen of the United States, and a resident of the borough of Manhattan, in the city, county, and State of New York, have invented a new and useful Lock, of which the following is a specification.

My invention is an improvement in locks, and is particularly an improvement in that 10 class of locks which are applied to the inner face of apartment or house doors for special protection against forcing. The object is to provide a lock of simple and strong construction, practically jimmy-proof, and requiring a minimum amount of cutting of the door and jamb.

In the accompanying drawings, forming a part hereof:

Fig. 1 is an inside elevation of a portion 20 of the door and door jamb, the door being closed;

Fig. 2 is a horizontal section through the door and jamb, the lock and keeper being in plan and the bolt shown projected;

Fig. 3 is a vertical section on the broken section line 3—3 of Fig. 2;

Fig. 4 is an inner face view of the lock, with the inner cover removed, showing the keeper in section, and the bolt projected;

Fig. 5 is a similar view, showing the bolt retracted;

Fig. 6 is a vertical transverse section on the line 6—6 of Fig. 4; and

Fig. 7 is a horizontal section on the line 35 7—7 of Fig. 1, showing the bolt projected.

The lock has a case 1, which is applied to the inner face of the door 2 by bolts 3, 3 and 4, 4. A removable wall or cover 5 is on the inner side of the case, next the door. In the 40 case is a bolt 6, consisting of twin upper and lower portions and a uniting rear portion 7. The upper rear limb of the bolt has a notch 8. The limbs of the bolt are guided in the interior of the case by a wall 39 having suitable openings or notches.

A knob 9 has a stem 10 rotatably mounted in the outer wall of the lock case. On the inner end of this stem is a double bit 11 to co-operate with the notch 8, so as to project 50 and retract the bolt. A spring 12 in the case, pressing upon flat shoulders connected with the stem of the knob serves to hold the same in one position or the other.

A detent 13 overlies the upper rear limb 55 of the bolt, being pivoted at its forward end on a screw 14 in the case, and pressed down-

ward by a spring 15. Said detent is preferably of skeleton channel or **U** form in cross-section to embrace the upper limb of the bolt, and has two longitudinally spaced 60 lugs 16 to co-operate with recesses 17 in the top of the bolt, so as to hold the same positively in both projected and retracted positions.

The bolt is also adapted to be actuated by a bit 18 of a key-cylinder 19 carried by the cover 5, opposite the knob. The detent 13 extends across the notch 8, so that it is lifted out of holding engagement with the bolt by either the bit 11 or the bit 18 preparatory 70 to the actuation of the bolt. The bits, it will be observed, lie within the twin-bolt structure, which is united by the portion 7 at the rear end, and the construction and relations are such that there is a very direct thrust on 75 the bolt without any tendency toward binding.

The case has an integral extension 20 to overlap the door-jamb 21, this extension comprising a wall 22 spaced from the end 80 of the wall 23 of the lock case and joined thereto by top and bottom portions 24, 25. In the end wall 23 of the case and the far wall 22 of the extension are alined openings 26, 27 for the passage of the bolt.

A keeper 28 is secured to the inner surface of the door jamb, that is to say, the surface which is opposed to the edge of the door, by screws 29, and is further secured to the jamb by a right-angular, laterally projecting flange 30, overlying the face of the jamb, that is to say the side facing the interior of the apartment, this flange having openings 90 for screws 31. The keeper has an inwardly projecting lip 32 which is received with 95 suitable slight clearance between the spaced walls 22 and 23 of the lock case, when the door is closed. This tongue, like said walls, is formed with twin openings, to permit the passage of the two members of the bolt. 100 Said bolt members when projected extend through the wall 22 of the extension, as seen in Fig. 7, and are guarded by vertical edge flanges 33, 34 on said wall, forming a channel wherein the bolt ends are enclosed, the 105 extension wall of the lock case being strengthened by these flanges so as to be rigid against prying.

The face flange 30 of the keeper is extended at 30^a above and below the inner 110 flange 28, and it is in these extensions that the screw holes for the screws 31 are pro-

vided. This is important because it is necessary or preferable to cut away the inner surface of the door-jamb so as to receive the flange 28 flush therewith, as shown in Figs. 5 2 and 7. By extending the portions 30^a of the face flange beyond the upper and lower ends of the flange 28, and therefore beyond the cut-out which is made in the inner surface of the door-jamb, the screws 30^a, upon 10 which heavy strain would fall in event of jimmying, are held in parts of the door-jamb which have not been reduced in thickness. In modern apartments the wood of the door-jamb is usually encased in metal trim, and 15 since the sheet-iron of such trim will not be cut away above or below the flange 28, the wood of the door-jamb at the regions which receive the screws 31 will be reinforced by such sheathing.

20 The flange 30, it will be observed, is applied to the outside of the face of the door-jamb, that is to say it is not sunk in by cutting a seat in this face, or cutting away the sheathing in the case of metal trim. This is 25 of advantage both in applying the lock and for the purpose of retaining maximum strength. To this end the peripheral wall 1^a of the lock case is extended rearwardly from the back wall 5 of the case in a deep flange 30 1^b proportioned so that the bolts 6 will be spaced from the face of the door to lie in a plane which enables them to register with the bolt-openings in the keeper lip 32 with the keeper applied to the door-jamb in the 35 manner described.

The lock case is secured to the door by pairs of screws 3 and 4 as stated. At the forward end the outer wall of the case is thickened at 37, to resist strain upon the 40 screws 4, this portion of the outer wall, the end wall 23, and the spaced extension wall 22 with the connecting elements, being of stout construction, as distinguished from the remainder of the case, which is not called 45 upon to withstand substantial strain. The case is preferably formed at the forward end with a flange 38 projecting rearwardly from the wall 23, this flange being let into the edge corner of the door when the lock 50 is applied.

What is claimed as new is:

1. A lock comprising a casing adapted to be applied to the face of a door and having an extension adapted to overlap the door-frame, with a bolt in the casing adapted to be projected across into the extension, in

combination with a keeper having two flanges at right angles to each other to be applied respectively to the face and inner surface of the door-jamb, and a lip having 60 a bolt-opening and projecting at right angles to the face flange to be received between the lock casing and its extension, said keeper flanges having screw-openings and the face flange being extended above and 65 below the inner flange and having its screw openings in said extensions, so that the screws which secure the keeper to the face of the door-jamb are set into regions which have not been cut away at the side for the 70 inner flange of the keeper.

2. A lock comprising a casing adapted to be applied to the face of a door and having an extension adapted to overlap the door-frame, with a bolt in the casing adapted to 75 be projected across into the extension, in combination with a keeper having two flanges at right angles to each other to be applied respectively to the face and inner surface of the door-jamb, and a lip having 80 a bolt-opening and projecting at right angles to the face flange to be received between the lock casing and its extension, said keeper flanges having screw-openings and the face flange being extended above and 85 below the inner flange and having its screw openings in said extensions, the lock case having means setting it out from the door to such extent that the face flange of the keeper is applicable to the outside of the 90 face of the door-jamb without setting in.

3. A door lock, comprising a lock case to be applied to the inner face of the door, said case having an extension beyond its end wall to overlap the door-jamb, said extension comprising a far wall spaced from the end wall of the case, and members uniting said walls, said end wall and far wall having aligned bolt openings, a keeper to be applied to the door-jamb having a tongue to project between said end and far walls of the lock case and containing an aligned bolt opening, and lock mechanism comprising a bolt in the lock case to be projected through the end wall of the case and the tongue of the keeper and through the opening of the far wall of the extension, the far wall of the extension having vertical edge flanges stiffening the wall and forming a channel 100 to guard the end of the bolt.

HOVAGIN SAKALIAN.
